A. L. Blanchard, of Albany, N.Y.
Letters Patent No. 1008. Dated June 1, 1858.

The schedule referred to in these Letters Patent and making part of the same.

To all whom it may concern:—

Be it known that I, A. L. Blanchard, of the City of Albany, County of Albany, and State of New York, have invented or produced a new and original design for an Aquarium, called "The Marine World," & I do hereby declare that the same is described and represented in the following specification and accompanying drawings. The large figure, 1, in the drawing represents the base of an Aquarium, in imitation of the seashore, with rocks, marine shells, of various kinds, and the leaves of aquatic plants shown in the drawing.

The small figure, 2, in the drawing is a representation of one of the columns that are to stand on each corner of the base. This column is a tree with a vine upon it, also a squirrel and bird upon it: and at the foot of the tree among the shrubbery, is shown a hunter with his dog and a gentleman and lady.

What I claim as my invention & production & desire to secure by Letters Patent End is the ornamental design for an aquarium, called "The Marine World," herein described and represented in the accompanying drawing.

Witnesses:—

S. H. Cosford.
